[57] CLAIM

The ornamental design for a high power spectacle lens, as shown and described.

DESCRIPTION

FIG. 1 is a front elevational view of a high power spectacle lens showing my new design;

FIG. 2 is a rear elevational view thereof; and,

FIG. 3 is a side elevational view thereof, the side opposite being a mirror image and the top and bottom plan views being identical.

It is noted that the right and left sides are completely symmetrical as is the top and bottom views which appear as the view in FIG. 3.

FIG. 1

FIG. 2

FIG. 3
